UNITED STATES PATENT OFFICE.

FRANK KUHN, OF DETROIT, MICHIGAN.

ELECTRIC-TERMINAL BOX.

1,119,839.

Specification of Letters Patent.

Patented Dec. 8, 1914.

Application filed March 8, 1913. Serial No. 752,875.

To all whom it may concern:

Be it known that I, FRANK KUHN, a citizen of the United States of America, residing at Detroit, in the county of Wayne and 5 State of Michigan, have invented certain new and useful Improvements in Electric-Terminal Boxes, of which the following is a specification, reference being had therein to the accompanying drawings.

10 The invention relates to electrical fittings employed for the terminal connections of various electrical instruments, and it is the object of the invention to obtain a construction adapted for alternative use with detachable and fixed electrical connections.

To this end the invention consists in the peculiar construction of a fitting adjustable to form a socket for receiving a terminal plug connector, and alternatively to form a 20 closed protecting casing or junction box.

In the drawings: Figure 1 is a cross section through the device as used with a detachable connector. Fig. 2 is a perspective view of the device with the detachable 25 cover removed. Fig. 3 is a horizontal section through the fitting, showing the same arranged as a junction box for permanent electrical connections.

A is a housing formed of suitable insulating material and preferably of substantially rectangular form. Within this casing are compartments B and C for the conductors of different potential, which compartments are separated from each other by 30 an intermediate partition D, and are open at one side for access to the connections.

E is a compartment arranged parallel and adjacent to the compartments B and C and separated therefrom by the partition F, said 40 compartment E being open at two sides of the casing which are at right angles to each other.

G and G' are metallic contact members arranged within the compartments B and C 45 and projecting through slots H into the compartment E. These metallic members G and G' are each provided with clamping plates I for connecting thereto electrical conductors J, which latter are inserted 50 through side slots K in the casing, and extend into the compartments B and C.

L is a cover for the case, which has an angle flange M adapted, in one position, to close the open compartment E, while, when 55 arranged in another position, said flange

lies adjacent to the opposite side of the case A, leaving the compartment E open.

With the construction as shown and described in use, the casing A is mounted in any convenient position upon the instrument to which connections are to be made—as for instance, by attaching it to the base or stand N of said instrument. If the electrical connections are to be permanent, one of the conductors forming the external circuit and one of the coöperating conductors which leads from the instrument, are both inserted through one of the apertures K, and are connected to each other by the contact G and clamping plate I, the bared metal being all inclosed within the insulating housing; the other conductor of the external circuit is similarly connected by the other contact and clamping plate to the coöperating conductor of the instrument. The cover 60 L is then secured to the casing A with its flange M arranged to cover the open side of the compartment E, as shown in Fig. 3 and in dotted lines in Fig. 1. If, on the other hand, a detachable connector is to be used 65 with the instrument, only the terminal conductors O of the instrument itself are led through the slots K into the compartments B and C, while the cover L is secured in reverse position, with the flange M adjacent 70 to the rear wall of the housing A, so as to leave an opening into the compartment E. This compartment thus forms a socket for 75 receiving a suitable plug conductor P, the contacts Q of which are detachably 80 engaged with the plates G and G'. 85

90 What I claim as my invention is:

1. The combination of a rectangular insulator casing recessed on one side to form separated compartments, and an adjacent 95 enlarged compartment, the latter being open at one side of the casing, contact members positioned in said separated compartments, said contact members projecting into said enlarged compartment, and a cover for the corresponding open side of all of said compartments, said cover being reversible and having a flange adapted in one position to lie adjacent a closed side of the casing, and in reversed position to close the opening in the side of the enlarged compartment 100 of the casing.

2. The combination of a rectangular insulator casing having a recess therein open upon two sides of the rectangle, and sepa- 105 110

- rated recesses open upon one side of the casing, contact members positioned in said separated recesses and extending into the recess which is open upon two sides, and an 5 angle closure member attachable to said casing in reversed positions, said closure member in one position completely closing said first mentioned recess, and in the reversed position leaving one side thereof open.
- 10 3. The combination of an insulator casing having a recess therein open upon two sides, means within said casing for making permanent connections between terminal connections leading thereto, and means 15 adapted to receive a removable plug to make a removable connection between the terminal

connections and a reversible angle closure member attachable to said casing in a plurality of positions, said closure member in one position lying adjacent to closed side of 20 opening and in reversed position closing both of the recess sides of the casing, whereby by the casing may serve as a closed casing for the permanent connection and in the reversed position of the closure serving as a 25 socket to receive a connector plug.

In testimony whereof I affix my signature in presence of two witnesses.

FRANK KUHN.
